(57) **CLAIM**

The ornamental design for an automotive engine computer unit cover, as shown and described.

DESCRIPTION

FIG. 1 is a front view of an automotive engine computer unit cover, showing our new design;

FIG. 2 is a rear view of the unit cover shown in FIG. 1; FIG. 3 is a top plan view of the unit cover shown in FIG. 1; FIG. 4 is a bottom plan view of the unit cover shown in FIG. 1;

FIG. 5 is a left side view of the unit cover shown in FIG. 1; FIG. 6 is a right side view of the unit cover shown in FIG. 1; and,

FIG. 7 is a perspective view of the unit cover shown in FIG. 1.

The article of the present design relates to an automotive engine computer unit cover. The parts shown by broken lines in the drawings form no part of the claimed design.

1 Claim, 3 Drawing Sheets
